UNITED STATES PATENT OFFICE.

JOSEPH A. STEINMETZ, OF PHILADELPHIA, PENNSYLVANIA.

MONEY-BOX.

SPECIFICATION forming part of Letters Patent No. 738,736, dated September 8, 1903.

Application filed April 3, 1903. Serial No. 150,882. (No model.)

To all whom it may concern:

Be it known that I, JOSEPH A. STEINMETZ, a resident of Philadelphia, in the county of Philadelphia and State of Pennsylvania, have 5 invented certain new and useful Improvements in Money-Boxes, of which the following is a specification.

This invention relates particularly to the construction of a metal box adapted for holding coins; and its primary objects are to provide a receptacle having parts that are readily formed and assembled to provide strength and security.

The nature and characteristic features of 15 the invention will more fully appear by reference to the following description and the accompanying drawings in illustration thereof, of which—

Figure 1 represents a plan view of a box 20 embodying my improvements. Fig. 2 represents a sectional view taken on the line 2 2 of Fig. 1, and Fig. 3 represents a sectional view taken on the line 3 3 of Fig. 1.

As shown in the drawings, the box A comprises 25 the sections A' and A², which are joined in abutting relation on the line a a. The sections thus joined have therein a reinforcing member A³, which conforms to the inner contour of the section A² and extends into the 30 section A', lapping the joint formed on the line a a between the sections. These parts are soldered or welded together at the joint a a, so as to form a solid construction. The top of the section A² is provided with the aperture a², and the top of the member A³ is provided with the aperture a³, which is made 35 smaller than the aperture a² to provide a seat a⁴ for a lid B. This lid is provided with the curved members B', having the hooks or lugs B² and B³ thereon, the members extending at right angles to the plane of the lid and lying in the notches a⁵, formed in the seat a⁴. The members B' when the lid is turned turn in

the recesses a⁶, so as to maintain the edge of the lid in close relation to the seat at the center of curvature of the members or hinges B', the part B² holding the edge of the lid in its relation to the seat and the part B³ preventing the lid from being opened beyond the point desired.

It is to be understood that the several members A', A², A³, and B are readily stamped to form from sheet metal the curved hinge B' being integrally connected with the lid B, and the parts are readily assembled and secured 50 together to provide a strong box having a secret hinge.

Having described my invention, I claim—

1. A receptacle formed of two abutting members, one of which has a lid opening therein, 60 a member fitting within the section having the lid opening and extending into the abutting section to lap the joint formed thereby, said member providing a seat, and a lid supported by said seat and adapted to close said 65 opening, substantially as specified.

2. A receptacle comprising two stamped sheet-metal sections joined in abutting relation, a member fitting within one of said sections and extending into the other so as to 70 lap the joint formed by the abutting sections, an aperture formed in one of said sections, a lid adapted to close said aperture, a seat formed by said member for supporting said lid, and a curved hinge projecting inwardly 75 from said lid and adapted to move in a recess formed in said seat, said recess engaging said hinge to control the movement of said lid, substantially as specified.

In testimony whereof I have hereunto set 80 my hand, in the presence of the subscribing witnesses, this 1st day of April, A. D. 1903.

JOSEPH A. STEINMETZ.
